US0D1002028S

(12) **United States Design Patent** (10) **Patent No.:** **US D1,002,028 S**
Jones et al. (45) **Date of Patent:** **** Oct. 17, 2023**

(54) **PLATE LIDS**(71) Applicant: **Meso Scale Technologies, LLC.**,
Rockville, MD (US)(72) Inventors: **Eric Jones**, Frederick, MD (US);
Jennifer Parker, Frederick, MD (US);
Manish Kochar, Rockville, MD (US);
Nicholas Sammons, Rockville, MD (US)(73) Assignee: **MESO SCALE TECHNOLOGIES, LLC.**, Rockville, MD (US)(***) Term: **15 Years**(21) Appl. No.: **29/778,234**(22) Filed: **Apr. 12, 2021****Related U.S. Application Data**

(62) Division of application No. 29/711,873, filed on Nov. 4, 2019, now Pat. No. Des. 918,415, which is a division of application No. 29/571,999, filed on Jul. 23, 2016, now Pat. No. Des. 867,614.

(51) **LOC (14) Cl.** **24-02**(52) **U.S. Cl.** **USPC** **D24/227**(58) **Field of Classification Search**USPC D24/227, 226, 230, 32, 216
CPC C12M 23/12; C12M 23/38; C12M 25/04
